Application June 29, 1932, Serial No. 619,820

25 Claims. (Cl. 246—227)

This invention relates to control for electrically operated track switches automatically operated from a railway car.

One object of this invention is to produce a system which will operate "power on" or "power off", the system as hereinafter described.

This invention more specifically relates to improvements in circuits and associated apparatus, and is further directed to a control in which 10 solenoids, contactors and circuits are grouped to produce the following objects:

First, to increase the life of the apparatus;

Second, to increase the speed of operation;

Third, to introduce a definite time element in 15 the switch operating circuit which will permit current to flow in the circuit for a predetermined time, and;

Fourth, to incorporate a positive means for 20 retaining the initial selection of the switch operating circuit as long as the current flows in this circuit.

These objects are attained by the apparatus illustrated in the accompanying drawings, in which—

25 Fig. 1 is a schematic drawing illustrating the conventional circuits encountered on a railway car.

Fig. 2 illustrates one form of the circuit connections of the system for accomplishing the 30 results heretofore mentioned.

Fig. 3 is a section of the control panel showing the general arrangement and construction of the relays employed in the system.

Fig. 4 is a section of relay Y taken through 35 the center line A, A.

Fig. 5 is an elevation of the holding means for relay X as viewed along center line B, B.

40 Fig. 6 is a modification of Fig. 5 in which the disposition of the associate coils are changed, and will be dealt with more specifically herein-after.

Fig. 7 illustrates a simplified embodiment of this switch operating system.

45 Fig. 8 illustrates a preferred embodiment of the circuits and associate apparatus of this system.

Throughout the various figures and drawings, like numerals and characters have been employed to designate identical parts in order to 50 convey the similarity of the several modifications.

In preparing the detailed description of this 55 invention, it is believed that a description dealing first with the construction and functions of

relays X and Y will render the operation of the various circuit modifications more apparent.

With reference to Fig. 3, it will be noted that relay Y, which is employed to control the current flowing to the switch operating solenoids, 5 is a departure from the conventional form of relay, and approaches a distinct form of electrically controlled apparatus. The relay Y is provided with a magnet frame F1 and a magnet core C6, secured thereto. Operating coils PC 10 and H are disposed about the magnet core C6. In one leg of the magnet frame F1, a bearing pin B is secured. Pivotal mounted on bearing pin B, are armatures Y1 and Y2. It will be noted that armature Y1 is arranged in comparatively 15 close proximity to core C6 and is further materially reduced in proportion over its associate armature Y2. It will be apparent to those skilled in the art that such an arrangement of armatures will cause armature Y1 to be affected an 20 appreciable time in advance of armature Y2 when current flows through the operating coils of the relay. Hereinafter the armature Y1 will be referred to as the small armature, while the associate armature Y2 will be referred to as 25 the large armature. Small armature Y1 is provided with a contact 3A and is arranged to register with contact post 3. It will be noted that contact post 3 and bearing pin B1 are supported on a common member, and therefore 30 permanently electrically connected. Large armature Y2 is not provided with the conventional form of electrical contacts. However, contact arm CA, which is pivotally mounted on bearing pin B1, is disposed in the line of travel 35 of armature Y2 such, that armature Y2 will mechanically engage the contact arm CA a predetermined time after it has been placed in operation. The dotted lines associated with relay Y illustrate the final operated position of armature Y2, and it will be apparent, that in this 40 position the contact arm CA will be forcibly driven out of contact engagement. Projecting member Y4 of armature Y2 is utilized to engage contact arm CA very close to its pivotal point 45 in the final operated position, for holding contact arm CA positively out of contact engagement. Armature Y2 is provided with driving plate D for engaging contact arm CA. Screw S5 of contact arm CA is a terminal connection 50 for a flexible connector placed between contact post 3 and contact arm CA, so that no current will flow through bearing pin B1. Armature CA is provided with a contact member 2, arranged to normally register with stationary con- 55

tact 1. Stationary contact 1 is mounted in contact post 1P which is secured in the insulating panel BA of the device. Armatures Y1 and Y2 are provided with contact stops 2P and 3P respectively. These stops are adjustable to several positions, and are provided with dowel pins to register with the small holes shown at the contact posts.

Relay X of Fig. 3 is employed to direct operating current of the device, to one or other of the switch operating solenoids. This relay is provided with the conventional form of relay contacts modified in such a manner so as to produce features not ordinarily found in conventional forms of relay equipment. Relay X is provided with a magnet frame F2 and a magnet core C1 secured thereto. Disposed about the core C1 is operating coil KL, the specific construction of which will be dealt with more specifically hereinafter. Bearing pin B3 of relay X is secured in magnet frame F2. Pivots mounted on bearing pin B3 is armature KLA. Armature KLA is provided with a weight W1 slidably mounted on rod R1. Weight W1 is utilized to control the current pickup of relay X, that is, when the weight is close to the pivotal point of the armature, a lesser current will be required through operating coil KL to affect the armature KLA, while, when the weight is extended to a position as illustrated, a greater current will be required through the operating coil KL to affect the armature KLA. Since a comparatively heavy current flows through the armature KLA a flexible connector S4 is provided between the magnet frame F2 and armature KLA for directing the current flow out of the path of the bearing pin B3.

The contacts of armature KLA, which can be more clearly seen by referring to Fig. 5, perform a dual function, that is, in addition to providing a low resistance electrical contact, they include magnetic qualities for completing a magnetic circuit. These contacts are arranged to register with contacts 4, 4A, and 5, 5A which likewise possess these same qualities.

With further reference to Fig. 5 it will be noted that magnet coils S1 and S2 are associated with contacts 4 and 5. Operating coil S1 associated with back contact 4 is disposed about a magnetic core. Adjacent the insulating panel BA, magnetic head J is located, while at the other end of the magnet coil a non-magnetic head J1 is located. Extending between the heads J and J1 is a magnetic shell V. It is apparent that the core extends through each of the heads J and J1. One end of the core is secured in the magnetic contact holder N while the other end of the core extends through the insulated panel BA for rigidly supporting the contact assembly to the panel. From the latter it will be apparent that when the contacts of armature KLA engage contacts 4, 4A, a completely closed magnetic circuit will be established. It will be further obvious, that when current flows through the magnet coil S1, the contacts 4, 4A will not only carry current, but will act to complete the magnetic circuit established by the magnet coil S1.

In Fig. 6 a modified form of a "magnetic contact" is illustrated. It will be apparent by referring to Fig. 6 that armature KLA in engaging contact post 4, will not completely close a magnetic circuit. However, the armature KLA in engaging the magnetic contact post 4 will complete the usual electrical circuit and as soon as current flows through the magnet coil S1,

contact post 4 will become a pole of the magnet S1, thereby magnetically holding armature KLA through magnetic leakage.

While the form illustrated in Fig. 6 has been extensively employed, it has not been found to be as effective as the form illustrated in Fig. 5.

With reference to Fig. 1, it will be noted that the circuits ordinarily associated with a railway car are illustrated by conventional symbols. The character T represents a trolley wire or overhead current conductor; character W designates a current collector of a railway car supported on the car by means of a trolley pole P1. Within the car are located heater circuits H1, lights L and air compressor F. These circuits while using current comparatively low in magnitude, play a prominent part in the operation of the invention, and will be referred to hereinafter as auxiliary currents. Character M designates the propulsion motors of the vehicle, while characters CO designate a controller for controlling the current flowing in the motor circuits. It is obvious to those skilled in the art that the currents flowing through the motor circuits, are comparatively large, and since these likewise play a prominent part in the operation of our invention, will be hereinafter referred to as car currents.

When the controller CO is in the off position no current will flow through the motors M of the car and this position will hereinafter be referred to as the "power off" position. When the controller CO is in the on position, a very heavy current will flow through the motors M, and this hereinafter will be referred to as the "power on" position.

Fig. 2 illustrates one embodiment of our invention, and relays X and Y heretofore described in detail are illustrated by conventional symbols. However, similar parts appearing in Figs. 3, 4, 40 5 and 6 are designated by identical numerals and characters. It is believed that a further detailed discussion of the parts and apparatus associated with Fig. 2 is not required, and that these parts can be more clearly discussed as the 45 description of Fig. 2 continues.

Normally the circuits shown in Fig. 2 are open, that is, no current flows from the trolley conductor T to the ground G. When the current collector W engages the trolley contactor P it 50 will first engage the contact member E, running out of contact engagement with the trolley conductor T. It will be obvious that the circuits of the car will be no longer directly completed from the trolley conductor T, but will be completed through the operating coil KL of relay X. This circuit being established from the trolley conductor T, through wire T1, wire T2, operating coil KL of relay X, wire E1, contact member E of trolley contactor P, through the current 60 collector W, trolley pole P, through the circuits of the car to the ground G. If, during the interval, the current collector W engages only the contact member E of trolley contactor P, the controller CO is in the off position, only the 65 auxiliary currents will flow through the operating coil KL of relay X. This current will not effect an energization of the operating coil KL of relay X sufficient to affect its armature KLA. The operating coil KL has a very low resistance, 70 generally consisting of six or eight turns of #6 copper wire, therefore the current which must flow through this operating coil to affect armature KLA is always greater than the auxiliary currents of the car, and must be greater than 75

the current required to operate the relays employed in the system. This current is always equivalent to 1 or 2 points power, i. e., one of two stages, stops or notches on the car controller, as may be used by the car operator. Therefore, it is obvious that if the car controller CO were closed, during the interval the current collector engaged only the contact member E of trolley contactor P, the heavy car currents would flow through the operating coil KL thereby sufficiently energizing the operating coil KL so as to affect its armature KLA.

From the foregoing it will be apparent that when the current collector W engages the trolley contactor P with "power off" the armature KLA of relay X will not be affected, and the relay X will retain the normal selection. However, when the current collector W engages the trolley contactor P with "power on", the armature KLA of relay X will be affected, thereby selecting and retaining its other operating position. Hereinafter when dealing with the description of the several circuit modifications when the "power on" position is referred to, it will be understood as to imply that the armature KLA has been raised from the normal contact engagement, and when the "power off" position is mentioned the armature KLA is being retained in its normal position.

When the current collector W advances, and engages the contact member C of trolley contactor P with the controller in the "power off" position, circuits will be established for energizing the track switch solenoid TM2. As soon as the current collector engages the contact member C, a circuit will be established for operating relay Y. This circuit being completed from the trolley conductor T, through wire T1, wire T2, operating coil KL of relay X, wire E1, contact member E of trolley contactor P, through the current collector W, contact member C of trolley contactor P, wire C1, resistance unit R, wire C2, high resistance operating coil PC of relay Y, wire C3, wire C4, low resistance operating coil H of relay Y, wire C5, armature KLA of relay X, back contact 4 of relay X, through the magnet coil S1, through wire 6, switch operating solenoid TM2, wire 8, wire 10, to ground G. The current flow established in this circuit will not be sufficient to energize the switch operating solenoids. As soon, however, as this circuit is completed the operating coil PC will be sufficiently energized to affect the small armature Y1 of relay Y. When the small armature Y1 engages its front contact 3, a circuit will be established for energizing the track solenoid TM2. This circuit being completed from the current conductor T, through wire T1, wire T3, fuse FU, contact 1, contact 2, contact arm CA, contact 3, small armature Y1, wire Y3, wire C4, low resistance coil H, wire C5, armature KLA of relay X, back contact 4, magnet coil S1, wire 6, track switch solenoid TM2, wire 8, wire 10 to ground G. The establishment of this heavy current flow to the track switch solenoid TM2 will sufficiently energize the operating coil H of relay Y so as to affect the large armature Y2 of relay Y, and will likewise sufficiently energize the magnet coil S1 of relay X so as to positively magnetically hold the armature KLA in engagement with contact 4. The operation of the large armature Y2, resulted in contact arm CA forcibly disengaging contacts 2 and 1 respectively, thereby opening the switch

operating circuit. Should the current collector W continue to engage contact member C of trolley contactor P, the operating coil PC of relay Y is so proportioned that both the small armature Y1 and the large armature Y2 will remain held in their operated positions. As soon, however, as the current collector W disengages the contact member C of trolley contactor P, the circuit of the operating coil PC will be opened thereby permitting armatures Y1 and Y2, and contact arm CA to be restored to normal.

When the current collector initially engages the trolley contactor P with "power on", armature KLA of relay X will be raised out of engagement with its back contact 4 and into engagement with its front contact 5. As the current collector advances and engages contact member C, relay Y will function in the same manner as described for the "power off" position. It is believed that this operation will be obvious to those skilled in the art, and that a further lengthy description is unnecessary.

Fig. 7 illustrates a simplified embodiment of the invention in which the operating coil PC of relay Y and the resistor R have been proportioned so that successive operations of armature Y1 and Y2 can be accomplished in the same manner as dealt with in Fig. 2. In Fig. 7 the operating coil PC is arranged to have a comparatively low resistance so that a heavy current can flow to either of the switch operating circuits previously selected. The number of turns of wire on the operating coil PC have likewise been proportioned, so that the relatively lesser current flow provided through resistance unit R will affect only armature Y1 but be of such magnitude as to retain both armatures Y1 and Y2 in their operated positions as long as the current collector W engages contact member C of trolley contactor P.

With further reference to Fig. 7, and with the current collector engaging the trolley contactor P with "power off", the collector will complete a circuit for energizing operating coil PC to such a degree that only the armature Y1 will be affected. This circuit being completed from the trolley conductor T, through wire T1, wire T2, operating coil KL of relay X, wire E1, contact member E of trolley contactor P, through current collector W, contact member C of trolley contactor P, wire C1, resistance unit R, wire C2, operating coil PC of relay Y, wire C5, armature KLA of relay X, back contact 4 of relay X, magnet coil S1 of relay X, wire 6, switch operating solenoid TM2, wire 8, wire 10, to ground G. This energization of the operating coil PC will affect the small armature Y1 bringing it into contact engagement with its contact 3. When the armature Y1 engages contact 3 a relatively greater current flow will pass through the operating coil PC for energizing the switch operating solenoid TM2. This circuit being completed from the trolley conductor T, through wire T1, wire T3, fuse FU, contact 1, contact 2, contact arm CA, contact 3, armature Y1 of relay Y, wire C3, operating coil PC of relay Y, wire C5, armature KLA of relay X, contact 4, magnet coil S1, wire 6, switch operating solenoid TM2, wire 8, wire 10 to ground G. The energization of operating coil PC with this greater current flow will cause large armature Y2 to be raised to its operated position illustrated by the dotted lines. As soon as armature Y2 is raised to this

position it will engage contact arm CA and forcibly disengage contacts 2 and 4. This operation will result in opening the operating current flowing in the switch operating circuit. As 5 dealt with in Fig. 2, it must be remembered that as long as the comparatively greater current flows in the switch operating circuit, the magnet coils S1 or S2 will be sufficiently energized to 10 positively retain armature KLA of relay X in its previously selected position. Should the current collector W continue to engage the contact member C of trolley contactor P, after the comparatively greater current flow is removed from the switch operating circuit, both armatures Y1 15 and Y2 will be retained in their operated positions. Operating coil PC, as heretofore mentioned, is so regulated that it will have sufficient power to retain these armatures in their operated positions by the circuit established through 20 the resistance unit R. As soon as the current collector disengages the contact member C, armatures Y1 and Y2 will be restored to normal, thereby permitting contact arm CA to be likewise restored to normal.

25 When the current collector engages the contactor P initially with "power on", the armature KLA of relay X will be affected and brought into engagement with its front contact 5, and when the collector advances and engages the 30 contact member C of trolley contactor P, the relay Y and magnet coil S2 will function in the same manner as heretofore described for energizing the switch operating solenoid TM1.

Fig. 8 illustrates a preferred embodiment of 35 this invention and even though it functions in the same manner as the systems described under Figs. 2 and 7, certain desirable features both in mechanical and electrical adjustments have been introduced. For instance, it will be noted that 40 the preferred embodiment selects the two coil arrangement of relay Y in preference to the single coil arrangement dealt with in Fig. 7. This selection permits a greater adjustment margin between the pickup values of armature 45 Y1 and Y2, thereby a greater time range can be effected by adjusting stops 2P and 3P dealt with in Fig. 3. It will likewise be noted that a heater resistor HR has been included, and is 50 permanently connected between the trolley conductor T and each of the switch operating solenoids TM1 and TM2. The introduction of this heater resistance HR maintains a small amount of heat in the control box, thereby 55 eliminating condensation and relative leakage often encountered in service. Similarly since this circuit passes to ground through each of the switch operating solenoids TM1 and TM2, a small amount of heat is maintained in the cylinder encasing these solenoids, thereby reducing 60 condensation therein to a small degree. It must be remembered, however, that the current flowing in this heater circuit is very small, and will not effect an energization of either of the switch operating solenoids sufficient to operate 65 the switch tongue O. It will be further noted that the operating circuit of relay coil PC of relay Y, does not pass through armature KLA of relay X as in the systems discussed in Figs. 2 and 7. The introduction of this feature has 70 been of material importance in the performance of the device. It was found under conditions encountered in service, that the small current broken by the disengagement of armature KLA and its back contact 4 in either of the systems discussed in Figs. 2 and 7, when the armature

KLA was affected at a time when the current collector W engaged the contact member C, over a period of time caused an accumulated deposit to be formed on the contacts to such an extent that the magnetic holding qualities of the contacts were greatly impaired. The placing of the resistance unit R between the solenoid connecting wires 6 and 7, as shown in Fig. 8, likewise enables an electrical adjustment to be made wherein the energization of the operating coil 10 PC for affecting the small armature Y1, is dependent upon the value of the multiple circuit formed through each of the track switch operating solenoids. This adjustment makes possible the rendering of the device completely inoperative 15 when either of the track solenoids or circuits of TM1 and TM2 become opened. These features while not affecting the spirit of the invention have materially contributed to the perfection of a device which will respond equally well 20 under all practical conditions of service.

With further reference to Fig. 8, when the current collector W initially engages the trolley contactor P with "power off", the armature KLA of relay X will not be affected. As soon 25 however, as the current collector advances and comes into contact engagement with contact member C, a circuit will be established for the operation of small armature Y1 of relay Y. This circuit being completed from the current 30 conductor T, through wire T1, wire T2, operating coil KL of relay X, wire E1, contact member E of trolley contactor P, through the current collector W, contact member C of trolley contactor P, through wire C1, operating coil PC of 35 relay Y, wire C3, wire C6, through the branches R1 and R2 of resistance unit R and each of the track switch operating solenoids TM1 and TM2 to ground G. This energization of the operating coil PC of relay Y will affect only the small 40 armature Y1 of relay Y. The operation of the small armature Y1 will complete a circuit for energizing the switch operating solenoid TM2. This circuit being completed from trolley conductor T, through wire T1, fuse FU, contact 4, 45 contact 2, contact arm CA, contact 3, small armature Y1 of relay Y, wire Y3, low resistance coil H of relay Y, wire C5, armature KLA, back contact 4, magnet coil S1 of relay X, wire 6, wire 6A, switch operating solenoid TM2, wire 8, wire 50 10 to ground G. The completing of this circuit resulted in the energization of the operating coil H of relay Y for affecting large armature Y2 and likewise energizes magnet coil S1 of relay X wherein armature KLA will be positively retained in contact engagement with its contact 4. The operating of large armature Y2 resulted in contacts 2 and 4 being forcibly disengaged discontinuing the current flowing to the switch operating solenoid TM2. If the current collector W continues to engage the contact members C after the large armature Y2 has been operated, the continued energization of the operating coil PC is proportioned so that only the large armature is retained in its operated 65 position. Referring to Fig. 3, it will be noted that the small armature Y1 in engaging contact post 3, will not engage core C6 of relay Y. In fact, as illustrated by the dotted lines, an appreciable air gap will remain in the magnetic circuit of the small armature. However, the large armature Y2, in being raised to its operated position, illustrated by the dotted lines, will engage core C6 of relay Y. By selecting the proper values for operating coil PC and the air gap of 70 75

the small armature Y_1 , the large armature Y_2 in engaging core C_6 will positively cause the small armature Y_1 to be restored to normal, by magnetically shunting the magnetic circuit of small armature Y_1 . This feature has been introduced into the preferred embodiment of the invention, since it definitely assures the small armature Y_1 opening the switch operating circuit before the large armature can release and permit contact arm CA to reclose the switch operating circuit at contacts 2 and 1. It will be obvious to those skilled in the art that this feature positively prevents the possibility of false switch operation upon disengagement of the current collector and trolley contactor, and will likewise be obvious that this feature may be introduced into the accompanying modifications or may be transferred to other switch operating systems with equal advantages. As soon as the current collector disengages the trolley contactor P large armature Y_2 will be restored to normal thereby permitting the contact arm CA to be restored to its normal position.

When the current collector engages the trolley contactor P initially with "power on" the armature KLA of relay X will be brought into contact engagement with front contact 5, and as the collector engages the contact member C , relay Y will function in the same manner as described above for energizing switch operating solenoid TM_1 .

While several modifications, and discussions dealing with the relations of the various parts associated with this invention have been treated quite thoroughly in the foregoing, there are, of course, other modifications and arrangements of the parts which may be made from that shown and disclosed in the accompanying drawings and specifications which is believed will still fall within the scope of this invention.

We claim:

1. In a system of the class described, the combination of a normally open operating circuit including an actuating solenoid, a relay adapted to selectively direct current in the said circuit through different parts of the said actuating solenoid, a second relay for controlling a flow of saturating current through either branch of the said solenoid, and a second circuit including the said second relay and solenoid, the said second relay operable to first close and then open the first said circuit upon a flow of current in the said second circuit.

2. In a system of the class described, the combination of an actuating solenoid, a relay operable to selectively direct current through different parts of the said solenoid, and a second relay for establishing a current flow to the said solenoid and arranged to automatically pick up upon a flow of current through the different parts of the said actuating solenoid.

3. In a system of the class described, the combination of an actuating solenoid, a relay operable to selectively direct current through different parts of the said solenoid, and a second relay for establishing a current flow to said solenoid, and arranged to automatically pick up upon a flow of current less than a saturating value through the said actuating solenoid.

4. In a system of the class described, the combination of an actuating solenoid, a relay operable to selectively direct current through different parts of the said solenoid, and a second relay operable to establish a current flow of a saturating value through the part of the

said solenoid selected in response to a flow of current less than a saturating value through the part of the said actuating solenoid selected.

5. In a system of the class described, the combination of an actuating solenoid, a relay 5 for selectively directing current through different parts of the said solenoid, a second relay means operable when the said second relay is energized to establish a current flow of saturating value in the said solenoid circuit, and other 10 means directly operated by said second relay after operation to discontinue the said current flow to the said actuating solenoid after a predetermined time.

6. In a system of the class described, the 15 combination of a normally open circuit including an actuating solenoid, a relay adapted to selectively direct current through different parts of the said solenoid, a second relay, and means directly operated by the energization of the 20 said second relay to first close and then open the said normally open circuit.

7. In a switch operating system, the combination of an actuating solenoid, a normally open operating circuit including the said solenoid, a relay for selectively directing current in the said circuit through different parts of the said solenoid, a second circuit of relatively high resistance including the said actuating solenoid, means affected by a current flow in the said 25 second circuit to close the first said circuit and means affected by a current flow in the first said circuit to discontinue the current flow in the first said circuit.

8. In a switch operating system, the combination of an actuating solenoid, a normally open operating circuit including the said solenoid, a relay for selectively directing current in the said circuit through different parts of the said solenoid, a second circuit of relatively high 40 resistance including the said actuating solenoid, means affected by a current flow in the said second circuit to close the first said circuit, and means affected by a current flow in the first said circuit to discontinue the current flow in the first 45 said circuit, said first and second means arranged to be retained in their operated conditions by a continued current flow in the said second circuit.

9. In a switch operating system, the combination of an actuating solenoid, a normally open circuit for conducting saturating current to the said actuating solenoid, a relay for selectively directing current in said circuit through different parts of the said actuating solenoid, a second 55 circuit of relatively high resistance connecting the said actuating solenoid, means affected upon a flow of current in the said second circuit to first close and then open the first said circuit, and means to prevent operation of 60 the said relay after its initial operation and while current is flowing in the first said circuit.

10. In a switch operating system, the combination of an actuating solenoid, a normally open circuit connecting the said actuating solenoid, a 65 relay for selectively directing currents through different parts of the said actuating solenoid, means operable to prevent an operation of the said relay to either of its positions as long as current flows in the said circuit.

11. In a switch operating system, the combination of an actuating solenoid, a normally open circuit connecting the actuating solenoid, a relay for selectively directing a current flow in the said circuit to different parts of the said 75

actuating solenoid, and electrically operated means associated with the said relay operable to prevent operation from either position of the said relay as long as current flows in the said circuit.

5 12. In a switch operating system, the combination of an actuating solenoid, a relay equipped with an operating coil and two independently pivoted armatures, one of said armatures operable when the said operating coil is energized to establish a current flow in the said solenoid circuit and the other said armature operable after the operation of the first said armature to discontinue the said current flow in the said actuating solenoid.

10 13. In a switch operating system, the combination of a contact pan and trolley wire, an electrically operated track switch, control means electrically connected to the trolley wire and pan and having other circuits leading to the pan and track switch for positioning the track switch in either of two directions when the pan is engaged by a current collector with "power on" or "power off", a normally open switch to direct operating current to the track switch and interposed in one of the circuits leading to the control means, a normally closed switch to control the current to the track switch and interposed in a circuit connecting the said normally open switch, normally de-energized means effective to close the said normally open switch when the collector engages the pan and to open the said normally closed switch to interrupt current to the track switch after a predetermined lapse of 15 time after the collector has engaged the pan and regardless of whether the collector continues to engage the pan or not, and means operating automatically upon engagement of the current collector with the pan to insure current to the track switch for the said predetermined time.

20 14. In a switch operating system, the combination of a contact pan and trolley wire, an electrically operated track switch, control means electrically connected to the trolley wire and pan and having other circuits leading to the pan and track switch for positioning the track switch in either of two directions when the pan is engaged by a current collector with "power on" or "power off", a normally open switch to direct operating current to the track switch and interposed in one of the circuits leading to the control means, a normally closed switch to control the current to the track switch and interposed in a circuit connecting the said normally open switch, normally de-energized means effective to close the said normally open switch when the collector engages the pan and to open the said normally closed switch to interrupt current to the track switch after a predetermined lapse of time after the collector has engaged the pan and regardless of whether the collector continues to engage the pan or not, and means operating automatically upon engagement of the current collector with the pan to insure current to the track switch for the said predetermined time, comprising an operating coil connected in series with the said one circuit leading to the control means and arranged to retain the said normally open switch operated until the said normally closed switch is operated to interrupt the current to the track switch.

25 15. In a switch operating system, the combination of a contact pan having a pair of contact members to be engaged by a current col-

lector, a trolley wire, an electrically operated track switch, a selector switch having control means connected to one contact member and the trolley wire, circuits leading from the selector switch to the track switch, a circuit leading from the selector switch connecting the other contact member and having included therein a coil, a switch controlled by the said coil and adapted to close a circuit from the trolley wire to the said circuit which includes the coil, selector switch, track switch and ground for the system, another switch controlled by the said coil and adapted to open the said circuit from the trolley wire after a predetermined time, the parts arranged to operate "power on" or "power off" to position the track switch and to prevent current flowing to the track switch after a predetermined time after the collector engages the pan and to maintain current to the track switch for said predetermined time regardless of the position of the collector after it has initially engaged the pan.

30 16. In a switch operating system, the combination of a pan, a trolley wire, an electrically operated track switch movable in different directions, an electrically operated switch to control the movement of the said track switch, circuits connecting the various parts to operate the said track switch to its proper position when the pan is engaged by a current collector with "power on" or "power off", one of the circuits being a path from the pan to the second said switch and having included therein a high resistance relay coil and a low resistance relay coil, means operated by the energization of the said coils to shunt said high resistance coil and to close a circuit from the trolley to a part of the said circuit which includes the low resistance coil and ground for the system, said means maintained in its operated condition by the energization of said low resistance coil to retain the last mentioned circuit connected to trolley, and other means operated by the energization of the said low resistance coil to open the said circuit from the trolley a predetermined time after initial energization of said coils.

35 17. In a switch operating system, the combination of a pan, a trolley wire, an electrically operated track switch movable in different directions, an electrically operated switch to control the movement of the said track switch, circuits connecting the various parts to operate the said track switch to its proper position when the pan is engaged by a current collector with "power on" or "power off", one of the circuits being a path from the pan to the second said switch and having included therein a high resistance relay coil and a low resistance relay coil, means operated by the energization of said coils to shunt said high resistance coil and to close a circuit from the trolley to a part of the said circuit which includes the low resistance coil and ground for the system, said means maintained operated by the energization of said low resistance coil to retain the last mentioned circuit connected to trolley, and other means directly operated by the energization of the said low resistance coil to open the said circuit from the trolley a predetermined time after initial energization of said high resistance coil, and means effective to re-establish energization of the said high resistance coil when the said other means is operated, and only when the current collector remains in engagement with said pan, to retain the said other means operated.

18. In a track switch operating system, the combination of an electrically operated track switch, a divided switch operating circuit, electrically operated means for selectively directing switch operating current in either branch of the said circuit to control the direction of movement of said track switch in either of two directions, a source of power, a contact pan to be engaged by a current collector and connections between the parts such that the system operates to connect the first mentioned means to the said source of power for establishing a flow of track switch operating current in one branch of the said circuit to effect an operation of the track switch to one of its positions when the collector engages the pan with "power off" and for establishing a flow of operating current in another branch of the circuit to effect an operation of the said switch to another position when the collector engages the pan with "power on", and electrically operated means responsive to the selective flow of the track switch operating current to compel the first said means to maintain current directed in the selected branch of the switch operating circuit as determined by the initial engagement of the current collector and contact pan.
19. In a track switch operating system, the combination of an electrically operated track switch, a divided switch operating circuit, electrically operated means for selectively directing switch operating current in either branch of the said circuit to control the direction of movement of said track switch in either of two directions, a source of power, a contact pan to be engaged by a current collector and connections between the parts such that the system operates to connect the first mentioned means to the said source of power for establishing a flow of track switch operating current in one branch of the said circuit to effect an operation of the track switch to one of its positions when the collector engages the pan with "power off" and for establishing a flow of operating current in another branch of the circuit to effect an operation of the said switch to another position when the collector engages the pan with "power on", electrically operated means responsive to the selective flow of track switch operating current to compel the first said means to maintain current directed in the selected branch of the said switch operating circuit as determined by the initial engagement of the current collector and contact pan, and means automatically operable to disconnect the first mentioned means from the source of power to interrupt the flow of switch operating current and to prevent further operation of the track switch as long as the current collector continues to engage the said pan.
20. In a switch operating system, the combination of a contact pan, a trolley wire, an electrically operated track switch movable to different positions when the pan is engaged by a current collector with "power on" or "power off", a divided switch operating circuit, a normally open switch for connecting the trolley wire and said switch circuit, said switch operating circuit having one of its branches normally connected to the track switch and the other branch normally disconnected, electrically operated means for alternating the connections and disconnections of the branches with the said normally open switch and track switch, a holding coil mounted on the electrically operated means and connected in series with the normally disconnected branch circuit to hold the branch circuit closed when the collector engages the pan with "power on", another holding coil mounted on the said electrically operated means and connected in series with the normally connected branch circuit to hold the branch circuit closed when the collector engages the pan with "power off", means controlling the said normally open switch to connect the said divided circuit to trolley when the collector engages the said pan, and means controlling the circuit from the trolley to the said normally open switch to disconnect the said divided circuit from the trolley after a predetermined time after the collector engages the pan and thereby de-energize the holding coil included in the previously selectively connected branch circuit.
21. In a switch operating system, the combination of a pan, a trolley wire, an electrically operated track switch movable to different positions when the pan is engaged by a current collector with "power on" or "power off", a divided switch operating circuit, a normally open switch for connecting the trolley wire and said switch circuit, said switch operating circuit having one of its branches normally connected to the track switch and the other branch normally disconnected, electrically operated means for alternating the connections and disconnections of the branches with the said normally open switch and track switch, a holding coil mounted on the electrically operated means and connected in series with the normally disconnected branch circuit to hold the branch circuit closed when the collector engages the pan with "power on", another holding coil mounted on the said electrically operated means and connected in series with the normally connected branch circuit to hold the branch circuit closed when the collector engages the pan with "power off", means controlling the said normally open switch to connect the said divided circuit to trolley when the collector engages the said pan, and means controlling the circuit from the trolley to the said normally open switch to disconnect the said divided circuit from the trolley after a predetermined time after the collector engages the pan and thereby de-energize the holding coil included in the previously selectively connected branch circuit.
22. In a switch operating system, the combination of an electrically operated track switch, a track switch operating circuit, a selector switch for positioning said track switch, a holding coil mounted on the normally engaged contact of the said selector switch, and means operating to energize said holding coil to hold said selector switch in a normal condition and to render it inoperative with power first off and then applied to the car motors.
23. In a switch operating system, the combination of an electrically operated track switch, a divided track switch operating circuit, a selector switch for positioning the said track switch having a normally disengaged front contact connecting one of the branches of said divided switch operating circuit and a normally engaged back contact connecting the other branch of said divided switch operating circuit, a holding coil mounted on each contact of the said selector switch and connected in series with the branch circuit connecting the respective contact, and

means operating to energize the holding coil selectively included in the switch operating circuit to hold the said selector switch in engagement with its selectively engaged contact as long as 5 operating current flows in the said switch operating circuit.

24. In a switch operating system the combination of an electrically operated track switch, a track switch operating circuit, a selector switch 10 for directing current in the said circuit to position the said track switch, a normally open front contact and a normally closed back contact for the said selector switch, a holding coil mounted on the said front contact and a holding coil 15 mounted on the said back contact, and means operating to selectively energize the said holding coils to retain the selector switch operating circuit in a selected condition whenever the sys-

tem is in use to establish a flow of current in the said track switch.

25. In a switch operating system the combination of an electrically operated track switch, a track switch operating circuit, a selector switch 5 for directing current in the said circuit to position the said track switch, a normally open front contact and a normally closed back contact for the said selective switch, a holding coil mounted on the said front contact and a holding coil 10 mounted on the said back contact, and means operating to selectively energize the said holding coils for a predetermined time to retain the selector switch in a selected condition whenever the system is in use to direct a flow of current 15 in the said switch operating circuit.
